UNITED STATES PATENT OFFICE.

CHARLES W. ADAMS, OF CHELSEA, ASSIGNOR OF THREE-FOURTHS TO
ARTHUR B. RROWNE AND EDGAR HARDING, BOTH OF CAMBRIDGE,
MASSACHUSETTS.

ELECTRIC-ARC LAMP.

SPECIFICATION forming part of Letters Patent No. 380,271, dated March 27, 1888.

Application filed October 6, 1887. Serial No. 251,646. (No model.)

To all whom it may concern:

Be it known that I, CHARLES W. ADAMS, of Chelsea, in the county of Suffolk and Commonwealth of Massachusetts, have invented a new and useful Improvement in Electric-Arc Lamps, of which the following, taken in connection with the accompanying drawings, is a specification.

In many "clutch-regulated lamps," a washer, through which a feed-rod passes, is attached to and receives its motion from an armature, and upon receiving such motion said washer clamps the feed-rod in opposite sides and raises it. There is a serious objection to this mode of operation, namely, the necessity for making the opening fit the rod closely, and the feed-rod in consequence often becomes jammed or abraded; hence unsteadiness in the light follows.

The object of my invention is to overcome any such objection by using, in connection with said lamp, a tilting clutch, which will bend and raise the feed-rod sufficiently to form an electric arc, and afterward will regulate the motion of the feed-rod according to the current of electricity passing through the lamp.

In the accompanying drawings, Figure 1 is a side view, partly in section, of an electric-arc lamp. Fig. 2 is a front view of same. Fig. 3 is a perspective view of a tilting clutch.

In Fig. 3, A represents the feed-rod of an electric-arc lamp, and B represents a part of a tilting clutch, and consists of a piece of metal or other suitable material, having an opening, C, for the insertion of feed-rod A, and having on one end slot E, extending into said opening C and being connected at the opposite end to the stationary piece K by the links I I.

F represents a clamping-lever working in slot E, being pivoted near one extremity at G, and at the other extremity, in any convenient manner, but preferably by small connecting-link L, to the armature M.

Y represents an adjustable or stationary stop, and is connected with the frame of said lamp at Z.

The operation of said tilting-clutch mechanism is as follows: The armature M being at-

tached by the action of the electric current passing through the lamp, raises, through the agency of L, the clamping-lever F, causing it to pivot at G, and at the same time to bind its upper end in the feed-rod A. Then the parts B and F, composing the tilting clutch, turn on the pivots connecting the small bars I I with the stationary piece K, thereby lifting the feed-rod A and forming the electric arc. When the electric current causes the armature M to drop, the feed-rod A is at the same time lowered until part B comes in contact with the adjustable or stationary stop Y, thereby causing clamping-lever F to loosen its hold on feed-rod A, which then descends by its own weight.

What I claim is—

1. In an electric-arc lamp, a perforated and slotted clutch, B, at one end permanently connected by a slotted joint and pivot with and tilting upon a stationary piece, as K, and again, at its opposite end, pivoted to a clamping-lever, F, the same to be used in connection with a feed-rod, A, substantially as shown and described.

2. In an electric-arc lamp, a tilting clutch consisting of a piece of metal or other suitable material, B, having an opening, C, and at one end a clamping-lever, F, of same material as above, pivoting at G in slot E, and again at its connection with link L, and at its opposite end being connected to the stationary piece K by links I I, the said clutch resting on adjustable stop Y, substantially as shown and described.

3. In an electric-arc lamp, the combination of a tilting clutch consisting of a slotted piece, B, the opening C, the clamping-lever F, the connecting-link L, the armature M, the small links I I, the stationary piece K, and the adjustable stop Y, with the feed-rod A, substantially as shown and described.

In testimony whereof I have signed my name to this specification, in the presence of two subscribing witnesses, on this 29th day of September, A. D. 1887.

CHARLES W. ADAMS.
